(57) **CLAIM**

The ornamental design for a fitment, as shown and described.

DESCRIPTION

FIG. 1 is a perspective view of the fitment;

FIG. 2 is a side elevational view of the fitment;

FIG. 3 is a side elevational view of the opposite side of the fitment;

FIG. 4 is a top plan view of the fitment; and,

FIG. 5 is a bottom plan view of the fitment.

The broken lines represent portions of the structure that form no part of the claim.
